The ornamental design for a portion of a container, as shown and described.

DESCRIPTION

FIG. 1 is a perspective top view of a portion of a container showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective bottom view thereof.

The broken line showing disclaimed regions in the figures and the remainder of the container are for illustrative purposes only and form no portion of the claimed design. The broken line immediately adjacent to the shaded region represents an unclaimed boundary of the design.
